UNITED STATES PATENT OFFICE.

JOSIAH FOWLER, OF ST. JOHN, NEW BRUNSWICK, CANADA.

MACHINE FOR BENDING SPRINGS.

SPECIFICATION forming part of Letters Patent No. 276,678, dated May 1, 1883.

Application filed March 31, 1882. (No model.) Patented in Canada, November 22, 1882, No. 15,836.

To all whom it may concern:

Be it known that I, JOSIAH FOWLER, of St. John, in the county of St. John and Province of New Brunswick, Canada, have invented certain Improvements in Machines for Bending Springs, of which the following is a specification.

My invention relates to the means for manufacturing those springs which consist of a series of superposed semi-elliptical leaves or spring-plates.

The invention consists in the machine for bending the plates consisting in the screw-press provided with concave and convex dies, the convex die being of greater width than the other, whereby the plates are supported across the entire face upon the under side, but subjected on the upper side to a pressure at the center only.

Referring to the accompanying drawings, Figure 1 represents a side elevation of my bending machine or press with the leaves in position therein to be acted upon. Fig. 2 is a detailed view, showing the manner in which the bending operation is performed and the action of the leaves upon each other during said operation. Fig. 3 is a cross-section of the same on the line $x-x$. Fig. 4 is a cross-section on an enlarged scale, showing the form of the leaves previous to the application of pressure thereto.

Referring to the drawings, A represents a strong upright frame, which may be of any suitable construction, and which is provided at the base with a rigid convex die or anvil, B, having its upper surface given a longitudinal curvature corresponding with that required on the inside of the springs to be produced. This anvil is made of a width as greater or greater than that of the spring, so as to give support to the bottom leaf throughout its entire under surface. The anvil is also provided on one side with a raised ledge or flange, a, to facilitate the adjustment of the blanks or leaves thereon. It is further provided at the center with the raised punch or protuberance b, for the purpose of keeping the plates in position. This protuberance may be simply employed to enter a previously-formed indentation in the bottom plate, or may be used to form the indentation in the act of bending the springs.

As shown in the drawings, each plate of the series will have an indentation on the under side and a corresponding elevation on the upper side, whereby they are retained in place 55 one upon another.

In the upper part of the frame, immediately over the anvil B, I mount a vertical screw, C, and upon the lower end of this screw I swivel a die or former, D, having its under side made 60 concave with a curvature corresponding with that required on the outer side of the spring. The die is made of about the same length as the anvil B, but of a width on the face less than that of the anvil or of the spring blanks 65 or leaves, in order that it may act only in a longitudinal line in the center or middle of the plates.

It will be observed that the two dies are of different curvatures on their faces, in order 70 that they may embrace closely between them springs having a greater thickness at the center than at the ends. By means of the screw the die D may be carried down upon the anvil B quickly and with great force.

I find in practice that it is highly essential to the successful carrying out of my invention that the upper die or former shall be carried downward very quickly and very forcibly, and that it shall be held in such manner as to prevent the slightest reaction or rebound, and, after using weights, cams, and other devices, I have found that the screw is peculiarly fitted for this purpose, and that when used in operating upon the spring plates or blanks its action differs materially from that of the other depressing devices named. In other words, I find that the screw gives to the dies a peculiar operation and effect not otherwise attainable. The die or former D is provided in its under 80 side with a central recess or cavity, c, corresponding in location with the protuberance b on the anvil, so as to admit the protuberance which will be formed upon the top leaf of the series.

In proceeding to manufacture a spring I provide a suitable number of flat blanks or leaves, E, of different lengths, as usual, arranging them in proper position one upon another, with the shortest at the top and the longest at the 90 bottom of the series. The series of blanks thus arranged is then placed upon the anvil

B, as shown in Fig. 1, and after being carefully adjusted in position the screw C is turned at a sufficiently high speed to bring the die or former D down very quickly and forcibly upon the blanks, thereby bending them to the required form and clamping them firmly upon each other between the two dies, the blanks receiving a quick, dead blow, and being retained solidly in place, whereby they are given the permanent "set" or curvature required.

It will be observed that during the descent of the die or former D it first acts upon the outer ends of the long blank and then successively and quickly upon the ends of the shorter blanks.

It will be observed that, as before noted, the successive blanks serve as formers or anvils for each other during the bending operation. This has been found in practice a matter of great importance and advantage, not only in that it permits the bending of the entire series of leaves at once, but in that as the leaves are bent upon and adapted to the surfaces upon which they are to remain permanently, a much closer, better, and more accurate fitting of the parts is secured than was otherwise attainable. When the plates or leaves formed

of the usual spring metal, which has thickened edges, are placed upon each other, supported by the broad anvil beneath and subjected to the pressure of the narrow former above, they are caused to assume a concavo-convex form in cross-section, as plainly represented in Fig. 3. The leaves thus formed possess much greater strength and stiffness in proportion to their weight than those made of flat form, and owing to their curvature they retain their position much more securely upon one another when in use.

The present invention is restricted to those matters and things which are specifically claimed herein, and as to all features which may be described and shown, but which are not claimed, the right is reserved to make the same the subject of separate patents.

Having thus described my invention, what I claim is—

In a spring-bending machine, the combination of the curved broad-faced anvil B, guard a, narrow die D, and screw C, as shown.

JOSIAH FOWLER.
